(57) **CLAIM**

The ornamental design for a control arm, as shown and described.

DESCRIPTION

FIG. 1 is a top, front, left perspective view of a new design for a control arm;

FIG. 2 a front view thereof;

FIG. 3 is a right side view thereof;

FIG. 4 is a top view thereof; and,

FIG. 5 is a bottom view thereof.

The rear view and the left side view are not visible for the claimed second new design of the control arm.

The broken lines show unclaimed portions of the control arm.
